UNITED STATES PATENT OFFICE

GEORGE M. NEWHALL, OF PHILADELPHIA, PENNSYLVANIA.

BUILDING CONSTRUCTION.

No. 902,898.

Specification of Letters Patent.

Patented Nov. 3, 1908.

Application filed April 29, 1907. Serial No. 370,779.

To all whom it may concern:

Be it known that I, GEORGE M. NEWHALL, a citizen of the United States, residing in Philadelphia, Pennsylvania, have invented 5 certain Improvements in Building Construction, of which the following is a specification.

My invention relates to building construction, and the object of my invention is to provide a building of such character, shape 10 and design as to present the maximum resistance to forces or elements that would tend to destroy the same, such building being especially intended to be earthquake-proof, and proof against fire resulting from 15 earthquake.

My invention is fully shown in the accompanying drawings, in which:

Figure 1, is a sectional elevation of a building embodying my invention, taken on the 20 line *a*—*a*, Fig. 2; Figs. 2 and 3, are sectional plan views of said building, taken on the lines *b*—*b* and *c*—*c*, respectively, Fig. 1; Fig. 4, is a sectional elevation of a modified 25 form of building embodying my invention, taken on the line *d*—*d*, Fig. 5; Figs. 5 and 6, are sectional plan views of such modified structure, taken on the lines *e*—*e* and *f*—*f*, respectively; Fig. 4, and Fig. 7, is a detached 30 sectional view, illustrating a detail of my invention.

The improvements in building construction forming the subject of my invention, comprise the use of curved walls forming as a main structure a building having its walls on 35 the arc of one or more circles, with which may be combined other curved wall extensions as convenient or desirable, or as the shape of the site may require or demand.

In one instance, an embodiment of my 40 invention may comprise a substantially circular building having an annular corridor on each floor situated intermediate the inner and outer walls, with rooms disposed in radial lines from the center or centers, and ex- 45 tending between said corridor and the inner and outer walls; such building having semi-circular or other curved exterior additions, preferably set at equidistant points. Other 50 instances of the same general character of construction and embodying my invention might comprise a main or central building having curved or semicircular extensions set on any radial line extending therefrom, such extensions gradually decreasing in area 55 of floor surface and exposed wall surface.

The building embodying my invention as

illustrated in Figs. 1, 2 and 3, comprises a pair of curved walls 1 and 2, concentrically disposed to form a substantially cylindrical structure and inclosing between said walls 60 space for rooms or offices 3 as desired; the space inclosed by the inner wall forming a light well 4, open at the top. Such building may be of any convenient height, divided into as many floors as desired. By preference, cor- 65 ridors 5 are disposed substantially midway between the inner and outer walls forming said building; such corridors dividing the series of rooms or offices disposed within the same on each floor and affording communica- 70 tion with the latter.

At certain points, which may be equidistant from each other, and on radial lines crossing each other at right angles, I provide curved or semicircular projecting portions, 75 four in number, extending from the base of the building, or the ground floor, as may be desired, to the roof; such projecting portions having radial entranceways 6 at the ground floor communicating with the annular cor- 80 ridors 5. Each floor is also provided with radial corridors 7 crossing the corridor 5 preferably at points equidistant from each other. Adjacent said radial communicating passageways or entrances, the elevators 8 of the 85 building are disposed in any suitable or desired manner.

At the base of the light well 4, if desired, I provide space 9 for a power plant to operate the various main and auxiliary engines, 90 motors or other devices used in the operation of the building for business or other purposes, and a stack 10 for the steam generating and heating apparatus may project centrally through said light well.

The building is constructed with a skeleton metal frame, and the inner and outer walls of the building are properly tied and braced for mutual support so as to afford the maximum resistance to the wind pressures, seismic and other disturbances, and by reason of its curved-wall design, the strains imparted will be compensated for by the various ties and bracing struts. In addition the walls and floors will be of fireproof material, such as 100 stone, brick or concrete, in combination with the usual metal reinforce.

At the top of the building, I provide a substantially flat roof 15 having a raised edge 16 to form a gutter, and upon said roof I 110 mount a tank 17 for the storage of water; the installation of which enables me to con-

struct a building of any height desired since with a roof tank of sufficient capacity the upper floors would always be in reach of adequate means for preventing the spread of fire.

The building as shown in Figs. 1, 2 and 3, might be substantially the same size as a city square, and for such arrangement the rounded tower-like projections are designed 10 for the corners of the square so as to provide adequate entrances to the building. The design of the entire structure insures a complete utilization of the space at hand; adequate supply of light and air for the internal 15 as well as the external offices; adequate heat and power for operating the building for business purposes, and, in addition to its manner of construction, such adequate water supply as to render the building absolutely 20 fire-proof.

In the form of building embodying my invention as disclosed in Figs. 4, 5 and 6, I have shown a structure particularly desirable for use on triangularly shaped lots, although not necessarily so limited, as it might be placed upon rectangular lots if it be desired that the building shall have a maximum amount of light and air. In this structure, a central building, comprising curved walls of 30 the same general character as that shown in Figs. 1, 2 and 3, is arranged, and from this central building, successively smaller curved or semicircular additions 25, 26 and 27, extend in two directions as noted. These additions, which may be in line or at any angle instead of the angle noted, serve to brace the main building from two sides, and having curved outer walls they offer the maximum resistance to wind pressure and seismic or 40 other disturbances. In such a form of building, radial corridors 28 extending through the wings join the corridors 5^a of the main or central section of the building, and entrances 6^a are placed at the ends of the wings and 45 also at the central part of the projecting portion of the main building.

In the arrangement shown in Figs. 5 and 6, the arc of the walls of the main building and both additions or extensions thereto are 50 in line on one side of the whole structure, and the same condition is true of the walls of the extensions to the buildings on the other side of the same; the curved portions being on general lines extending at an angle and meeting in front of the main entrance of the building.

This type of building has been designed and is particularly applicable for use in those sections of the world subject to seismic disturbances, as the arrangement of curved walls, some of which are disposed concentrically and all of which are braced for mutual support, affords the maximum degree of stability. By having a water tank the full size of the roof, ample means are provided 65 for flooding the building in case of fire from any cause, thereby making the structure absolutely fire-proof.

I claim:

1. An earthquake proof structure the plan 70 of which covers substantially a polygon, comprising a cylindrical main building having a curved outer wall and a concentric inner wall forming a central court, and a series of connected curved additions projecting 75 directly from said main cylindrical building, each side of the polygon being tangent to the main building and also tangent to at least two of the curved wall additions.

2. An earthquake proof structure the plan 80 of which covers substantially a polygon, comprising a cylindrical main building having a curved outer wall and a concentric inner wall forming a central court, a corridor extending around the building between the 85 inner and outer walls, and a series of curved additions projecting from said main building at several points above its circumference, each side of the polygon being tangent to the main building and also tangent to at least 90 two of the curved wall additions.

3. An earthquake proof structure the plan 95 of which covers substantially a polygon, comprising a cylindrical main building having a curved outer wall and a concentric inner wall forming a central court, and a plurality of connected curved wall additions projecting from said main structure at one or more points and extending to the top of the building, each side of the polygon being tangent to the main building and also tangent to at least two of the curved wall additions, in combination with a curved wall water tank 100 covering the roof of said structure.

In testimony whereof, I have signed my 105 name to this specification, in the presence of two subscribing witnesses.

GEORGE M. NEWHALL.
